L. M. BOYLE,
VEHICLE CARRIER,
APPLICATION FILED MAR. 4, 1919.

1,320,833.

Patented Nov. 4, 1919.

Inventor,
Louis M. Boyle.

By

Louis M. Boyle

His Attorney.

UNITED STATES PATENT OFFICE.

LOUIS M. BOYLE, OF LOS ANGELES, CALIFORNIA.

VEHICLE-CARRIER.

1,320,833.

Specification of Letters Patent.

Patented Nov. 4, 1919.

Application filed March 4, 1919. Serial No. 280,528.

To all whom it may concern:

Be it known that I, LOUIS M. BOYLE, a citizen of the United States, residing at Los Angeles, in the county of Los Angeles and State of California, have invented new and useful Improvements in Vehicle-Carriers, of which the following is a specification.

This invention relates to vehicle carriers, and more particularly to carriers for mounting upon a running-board or other structural part of automobiles for carrying canteens or other liquid receptacles. In ordinary practice, particularly in arid and waterless countries, it is customary to carry a canteen upon the running-board of an automobile, so that a plentiful supply of water for potation or for radiator cooling may be available between points at which fresh supply of water may be obtained. Such carriers as usually constructed are rigid in organization and merely support the canteen in fixed position, so that it may be withdrawn for use and then returned to the carrier to be again held in fixed or upright position.

In accordance with the present invention I provide a suitable carrier provided with a tilting or swinging or rocking frame adapted to receive the canteen or other container, and provide means for fastening the canteen removably in place, and also locking means for normally maintaining the tilting frame in horizontal position or position of service; and I associate these locking means with the retaining or holding means, so that when the canteen or container is fastened in the carrier the locking means are rendered and maintained effective. When the canteen is released the locking means automatically frees the tilting frame so that it can be tilted or tipped with the container, to permit of decanting liquid without removing the canteen from place. This is of great convenience in pouring out water or other liquid into a glass or tumbler, or in washing the hands in a stream from the tilted container, and in many other instances. It obviates the necessity of lifting the canteen from the carrier, and as soon as the carrier is tilted back to upright position and the retaining means are again rendered effective, the locking means likewise are again rendered effective to prevent tilting or tipping or rocking of the frame with the container until the retaining means and locking means are manipulated to release the container frame.

The invention has for its object to provide an improved vehicle carrier of the kind mentioned which will be generally superior in efficiency and serviceability, taken in conjunction with relative inexpensiveness and simplicity of construction and reliability and convenience in action and use, as well as durability and sightliness in appearance and which may be readily installed in position or detached from the vehicle or its running-board.

With the above and other objects in view, the invention consists in the novel and useful provision, formation, construction, combination, association and inter-relation of parts, members and features, all as herein-after described, shown in the drawing, and finally pointed out in claims.

In the drawing:

Figure 1 is a fragmentary side elevation of an automobile showing the improved carrier, with the canteen, applied to the running board thereof;

Fig. 2 is an enlarged detail side elevation of the carrier in detached position, with the locking means effective;

Fig. 3 is a similar view showing the locking means ineffective and the container frame tilted;

Fig. 4 is a fragmentary front elevation of the structure shown in Fig. 2;

Fig. 5 is a view similar to Fig. 4 showing the locking means ineffective;

Fig. 6 is a fragmentary side elevation of a canteen or container which may be used in connection with the invention and showing the retaining member applied thereto, and partially sectioned;

Fig. 7 is a fragmentary top plan view of part of the retaining means or member shown in Fig. 6; and,

Fig. 8 is an isometric view of the showing in Fig. 7.

Corresponding parts in all the figures are designated by the same reference characters.

Referring with particularity to the drawing, A designates an improved carrier shown as connected by clamps *a* with the running board B of an automobile C. The carrier A comprises upright side members *b*, rising from the clamps *a*, and held by the clamps, and threaded adjustable portions 9 thereof, firmly and securely to the running board. Between the tops of the side members, by pivotal connections 10 is suspended a tilting or swinging or rocking or pivoted

container frame member or basket *c*, which comprises spaced side bars 11 and end bars 12, and a downwardly bowed or looped bottom wall 13, such parts 11, 12 and 13 being formed and adapted to snugly receive and fit the canteen or other container *c*. A retaining member *D* is provided for the canteen or container, the same comprising a flexible device or strap 14 secured at one end fixedly to one of the upright members *b* of the fixed frame portion and adapted to be applied to and releasably engaged with a slidably member *d* mounted in connection with the other upright frame member *b* so as to slide up and down the same. To that end the member *d* may consist of a metallic plate having side clips or bent lugs 15 which slidably embrace the edges of the upright *b*, and an inwardly directed fixed lug 16 which is received within an elongated slot 17 ranging upwardly and downwardly in the respective member *b*. The upper end of the plate of the member *d* is bowed outwardly, as at 17, and provided with a buckle device 18 adapted to receive the free end of the strap or retainer member 14 after the same has been passed over the top of the canteen or container *c*. Between its ends the strap 14 is provided with a box-like device 19, having top walls 19^a and side walls 19^b, but being open at the ends, and this device 19 is placed over a spout 20 of the canteen, and when the strap 14 is tightly fastened down by means of the buckle device 18 it securely and positively holds the canteen in place and prevents its being inadvertently removed from the tilting frame member *c* and likewise tends to effectively anchor and steady the canteen in such tilting frame member wherein it is held between and upon the parts 11, 12 and 13. When the strap 14 is buckled down, it of course holds the lug of the member *d* in raised position, determined by the engagement of the lug 16 with the top end portion of the elongated slot 17, and the side lugs or clips 15 are held in engagement with the end bars 10 of the tilting frame *c* so as to prevent that frame from tilting or rocking, holding 50 the frame and the canteen in upright position. When the strap 14 is freed from the buckle device 18, the member *d* of course drops, automatically releasing the tilting frame *c* from the locking action of the lugs 55 15, and the frame *c* may be tilted with the container so as to permit of decanting the liquid therein. The box-like device 19 is of course freed from the spout 20 of the canteen, and the usual stopper may then be withdrawn to permit access to the contents 60 of the container.

It is obvious that many changes and variations may be made in practising the invention, in departure from the disclosure of 65 the foregoing description and the drawing,

all without departing from the true spirit of the invention.

Having thus disclosed my invention, I claim and desire to secure by Letters Patent:

1. A device of the character described, including a supporting frame, a tiltably mounted basket carried by the supporting frame and adapted to receive a removable container, means for locking the basket against tilting, and retaining means for holding the container in the basket, said retaining means being associated with the locking means to hold the latter in operative position. 75

2. A device of the character described, including a supporting frame, a tiltably mounted basket carried by the supporting frame and adapted to receive a removable container, means for locking the basket against tilting, and a retaining strap extending across the container to hold it in position within the basket, said retaining strap also engaging the locking means to hold the latter in operative position. 80

3. A carrier of the character disclosed, provided with a tilttable member adapted to support a container or other device, locking means for maintaining the tilttable member and container in a predetermined position, and a retaining device for the container and adapted to hold the same effective; said locking means comprising a member adapted to retreat by gravity from effective position upon disengagement therefrom of such retaining device. 90

4. A device of the character described, including a supporting frame, a tiltably mounted basket carried by the supporting frame and adapted to receive a removable container, a slidable lock for holding the basket against tilting, and retaining means extending across the container to hold the same within the basket, said retaining means being detachably connected with the sliding lock to hold the latter in operative position. 105

5. A carrier of the character disclosed, provided with a tilttable member adapted to support a container or other device, locking means for maintaining the tilttable member and container in a predetermined position, and a retaining device for the container and adapted to be inter-engaged with the locking means to hold the same effective; said locking means comprising a member adapted to retreat from effective position upon disengagement therefrom of such retaining device; said carrier being provided with a frame in connection with which said tilttable member is mounted, and said locking means being slidably mounted in connection with said frame. 115

6. A carrier of the character disclosed, provided with a tilttable member adapted to 130

support a container or other device, locking means for maintaining the tilttable member and container in a predetermined position, and a retaining device for the container and adapted to be inter-engaged with the locking means to hold the same effective; said locking means comprising a member adapted to retreat from effective position upon disengagement therefrom of such retaining device; said carrier being provided with a frame in connection with which said tilttable member is mounted, and said locking means being slidably mounted in connection with said frame; said frame being provided with uprights between which said tilttable member is mounted, and said locking means comprising a member slidably mounted in connection with one of said uprights and adapted to be engaged with said tilttable member to hold the same against tilting.

7. A carrier of the character disclosed, provided with a tilttable member adapted to support a container or other device, locking means for maintaining the tilttable member and container in a predetermined position, and a retaining device for the container and adapted to inter-engage with the locking means to hold the same effective; said locking means comprising a member adapted to retreat from effective position upon disengagement therefrom of such retaining device; said carrier being provided with a frame in connection with which said tilttable member is mounted, and said locking means being slidably mounted in connection with said frame; said frame being provided with uprights between which said tilttable member is mounted, and said locking means comprising a member slidably mounted in connection with one of said uprights and adapted to be engaged with said tilttable member to hold the same against tilting, said upright with which said locking means is associated being provided with an elongated slot, and said locking means having a projection adapted to travel in said slot, and other projections holding the

locking means in slidable connection with said upright and adapted to directly engage said tiltable member.

8. A carrier of the character disclosed, provided with a tiltable member adapted to support a container or other device, locking means for maintaining the tiltable member and container in a predetermined position, and a retaining device for the container and adapted to be inter-engaged with the locking means to hold the same effective; said locking means comprising a member adapted to retreat from effective position upon disengagement therefrom of such retaining device; said carrier being provided with a frame in connection with which said tiltable member is mounted, and said locking means being slidably mounted in connection with said frame; said frame being provided with uprights between which said tiltable member is mounted, and said locking means comprising a member slidably mounted in connection with one of said uprights and adapted to be engaged with said tiltable member to hold the same against tilting; said locking means being provided with a buckle device with which said retaining member is directly engaged. 75

9. A device of the character described, including a supporting frame, a tiltably mounted basket carried by the supporting frame and adapted to receive a removable container, a slide mounted upon the frame 80 for engagement with the basket to lock the basket against tilting, and a retaining strap extending across the top of the container and detachably connected to the slide, the tension of the strap holding the slide in 85 operative position when the strap is tightened.

In testimony whereof, I have signed my name to this specification in the presence of two subscribing witnesses.
